JOSEPH A. WHITE, OF MELROSE PARK, PENNSYLVANIA, ASSIGNOR TO THE MOORE & WHITE COMPANY, OF PHILADELPHIA, PENNSYLVANIA, A CORPORATION OF PENNSYLVANIA

WIRE APPLYING MECHANISM FOR FOURDRINIER PAPER MAKING MACHINES

Application filed December 4, 1930. Serial No. 500,097.

One object of my invention is to provide suitable means for storing, supporting and applying the endless wire of a Fourdrinier paper-making machine.

5 A further object of the invention is to provide a means whereby the wire can be transferred from the supporting means to the machine without undue friction or damage to the wire.

10 A still further object of the invention is to provide a support for the wire as it is drawn from the poles at the side of the machine to its position on the Fourdrinier machine.

15 The invention also relates to certain details which will be described hereinafter.

In the accompanying drawings:

Fig. 1 is a side view of a Fourdrinier paper-making machine, which shows the posts and poles at the side of the machine for supporting the wire prior to its being transferred to the machine. This view illustrates the truck applying the wire to the poles at the side of the machine.

25 Fig. 2 is a view similar to Fig. 1, showing the wire in position in the machine prior to the removal of the posts and poles at the side of the machine;

Fig. 3 is a plan view;

30 Fig. 4 is a transverse sectional view on the line 4—4, Fig. 1;

Fig. 5 is a front elevation of the truck on which the wire is mounted prior to its application to the machine;

35 Fig. 6 is a side view of the truck shown in Fig. 5;

Fig. 7 is an enlarged sectional view of the upper portion of the truck, on the line 7—7, Fig. 5;

40 Fig. 8 is an enlarged view of one of the clamps and the rope which draws the wire onto the machine;

Fig. 9 is a view of two poles, showing the connection, one of the poles being partly in section; and

45 Fig. 10 is a perspective view of one of the posts.

Referring to the drawings: 1 is a Fourdrinier paper-making-machine, which may be of any suitable type. The particular ma-

chine shown in the drawings forms the subject of a separate application, Serial No. 497,039, filed by me on the 20th day of November, 1930. This machine consists of supporting beams 2, spaced a given distance apart, and these beams extend the full width of the machine and rest upon the usual foundation. Each supporting beam is made in the form of a single hollow casting, having an upper member 4 and a lower member 5. 55 These two members are connected at one end only by a vertical member 6. The upper and lower members are spaced apart to form a throat 3 for the return run of the wire, and when the machine is in operation the outer end of the upper member is supported by a removable block 7, shown by dotted lines in Fig. 4. This block is removed when it is necessary to withdraw an old wire and to place a new wire in position, the beams being 60 of sufficient strength to temporarily support the structure.

The Fourdrinier machine is made in two sections. 9 is a paper-making section, having rollers 10 for supporting the upper run 75 of the wire a, and 11 is the suction box section of the machine. The lower run of the wire a passes through the throats 3 of the supporting beams 2. 8 is the breast roll, mounted in fixed bearings 12 on the making 80 wire section, and 13 is the couch roll at the delivery end of the machine. The bearings 14 of the couch roll rest normally on an adjustable base 15. The base is longitudinally adjusted by means of a screw 15a on a foundation plate 17. When the wire is to be placed upon the machine, the adjustable base 15 is moved from its normal position, shown by dotted lines in Fig. 1, to the position shown in full lines in said figure, and the bearings 85 14 are attached to a bracket 16 by bolts 16a, so that the couch roll is suspended from the brackets when the old wire is removed and the new wire placed in position.

By moving the couch roll to the position 95 shown in full lines in Fig. 1, there is sufficient slack in the wire a to allow the old wire to be removed from the machine and a new wire drawn onto the machine from the supporting rolls.

- 18, 18a are two rockers for the paper-making section of the machine. The rocker 18 is adjustably mounted on a cam shaft 19 adapted to bearings 20 secured to the beam 2 at the forward end of the machine, while the rocker 18a is mounted on a projection 21 of the suction box section of the machine. This mechanism is fully set forth and claimed in the pending application referred to above.
- 10 Located in the floor some distance from one side of the Fourdrinier machine are a series of floor sockets 22, and mounted in these sockets are posts 23. These posts are tubular in the present instance but they may be of any shape desired, and each post has two brackets 24 and 25, one at the upper end and one at the lower end, as clearly shown in the drawings. Each bracket has a cylindrical section 26, through which the post extends, and is fastened to the post by a set screw or other fastening device, and projecting from each bracket is a socket 27, and the socket is open at the top, so that a pole 28 can be placed in the socket.
- 15 On the frame of the Fourdrinier machine are a series of sockets 29 and 30, the series of sockets 29 being on that side of the machine opposite the posts, while the other sockets 30 are at the other side of the machine. These sockets are open at the top and support poles 31. It will be noticed that the poles 31 are in direct line with the poles 28, in fact they are a continuation of the poles 28, being connected by a pin and socket joint shown in Fig. 9. The pin 32 in the present instance is secured to the poles 31 and extends into the hollow poles 28, so that the joint is such that there is no obstruction to the wire as it is drawn from the poles 28, to the poles 31. The lower poles 28 are on a line with the upper surface of the lower member 5 of the supporting beam 2. Other poles are in alignment with the upper surface of the wire-supporting rolls 57. Short posts are used to support the inner ends of the poles 28, which are opposite the rolls 57. In order to place the wire on the poles 28, without breaking or injuring the wire, I provide a truck 33, Figs. 5 and 6, which truck has a frame 34 on which is a platform 35. 36 are casters which allow the truck to be freely moved from one place to another.
- 20 37 are standards projecting upwardly from the frame 34. These standards are spaced apart a greater distance than the width of the making wire α as shown clearly in Fig. 5, and on each standard is a bracket 38, and on one arm of each bracket are two rollers 39, and the other arm 40 of each bracket is turned up at its outer end 41 and is arranged to support the number of poles 28 within the loop of the wire, as shown in Fig. 1.
- 25 The wire is rolled upon a spool, which consists of two of the poles 28 and two heads 42. These heads are grooved on the periphery and rest upon the rollers 39 of the brackets 38. There is a guard 43 on the outer side of the bracket to prevent the heads of the spool from being accidentally displaced. 70 The arms 40 of the bracket on which the poles 28 are mounted, carry a sufficient number of poles, which are to be located inside of the endless making wire, as indicated in Figs. 6 and 7, and the platform 35 has a flange 44 75 between which and the standards 37 can be located a number of the poles 28, which are to be located outside of the endless making wire.
- 30 On the side of the Fourdrinier machine 80 opposite the side on which the poles are mounted, is a means for drawing the wire onto the machine, and consists in the present instance of a longitudinal shaft 45 having a hand wheel 46; if the shaft is to be 85 turned manually. The shaft is mounted in brackets 47, secured to an angle beam 48 attached to the supporting beams 2, and on the shaft are a series of drums 49, on which are wound the drawing-in ropes or belts 50 and 90 51.
- 35 At the free end of each rope is a snap hook 52 in the present instance, to which is attached a clamp 53, consisting in the present instance of a base plate 54 and a clamping plate 55, which are clamped to the sides of the making wire by clamp screws 56, or other suitable devices, when a wire is in position on the poles 28 at the side of the Fourdrinier machine. The clamps are secured to the edge 100 of the wire as shown in Fig. 8, and by turning the shaft 45, the upper run of the wire and the under run of the wire are drawn simultaneously onto the Fourdrinier machine, the poles 31 supporting the upper run 105 of wire as the wire is drawn onto the machine; the lower run of the wire resting on the upper surfaces of the lower members 5 of the supporting beams 2 and tension rollers 57 of the Fourdrinier machine. The upper 110 surface of the member 5 may be sheathed with copper plates 58 to prevent chafing of the wires.
- 40 When a wire is to be replaced, the old wire is removed from the machine in any suitable 115 manner. The truck on which the new wire has been previously mounted, in the manner shown in Figs. 5, 6 and 7, is removed from the store room and the posts 23 are mounted in their sockets 22. Then the truck is moved 120 longitudinally along the side of the machine between the posts 23 and the machine, and one of the poles 28 is placed in position on the upper socket bracket 24 of the first post 23, and is connected in alignment with the 125 pole 31 on the machine and another pole 28 is placed in the lower socket 25 of the first post 23 and the socket 59 at the side of the machine. This pole is in alignment with the upper surface of the lower member 5 of the 130

first supporting beam 2. Then as the truck is moved forward and other poles are placed in position, as shown in Fig. 1, so as to properly support the wire, and as the truck continues its movement in the direction of the arrow, Fig. 1, the wire is hung on the poles until the last pole is reached, the wire encircling the couch roll 13. Then the truck is removed.

In the present instance six posts are shown but the number of posts will depend upon the length of the Fourdrinier machine. After the wire has been placed on the several poles, as shown in Fig. 2, then the clamps 53 are secured to the edge of the wire nearest the Fourdrinier machine, and the shaft 45 turned by the hand wheel 46 or other suitable appliance and the upper and lower runs of the wire are simultaneously drawn into the machine, the breast roll and the couch roll being in the position shown in full lines in Fig. 2, allowing the wire to freely pass over these rolls. When the wire is in position in the machine, the poles 31 are removed and the blocks 7 are placed in position under the overhanging portion 4 of the beam and the poles 28 are removed, and the posts 23 withdrawn from their sockets. The empty truck is returned to the storeroom, where another wire can be mounted thereon for future use.

In some instances where there is sufficient space, the posts 23 may be permanently located in the floor but in most paper-making mills the space is limited and it is desirable to make the posts 23 removable so as to allow a clear floor space.

At one side of the machine is the shaking mechanism 60, for the paper-making section of the machine. This mechanism consists in the present instance of three standards 61, having levers 62 connecting the shaking mechanism on each post with the paper-making section of the machine. The shaking mechanism is driven by a motor 63 in the present instance, geared to a shaft 64 common to all the standards. This shaking mechanism forms no part of the present invention. It is fully described and claimed in the co-pending application referred to above.

In place of the short posts at the inner side of the poles 28, which are opposite the rolls 57, brackets may be provided on the frame, which support the rolls 57, without departing from the invention, and in some instances the poles may be spaced in such a manner that they will be located between the supporting beams and the rolls 57, and suitable supporting posts may be used to carry these poles.

In some instances the pin socket joint which connects the two poles, as shown in Fig. 9, may be omitted and the bracket 29 may be extended so as to carry both poles, as shown by dotted lines in Fig. 4. The rear bracket forms an abutment for the poles, as

shown in Fig. 4, as the wire is drawn onto the machine.

By the above description it will be seen that the making wire can be readily mounted on the Fourdrinier machine without buckling or injuring the wire in any manner, as there is enough slack to allow the wire to be drawn onto the machine, and as the posts and poles are removable it allows for free space at the side of the machine for ready access to the machine at any time, and by locating poles on the upper portion of the machine, the upper run of the wire can be drawn from the poles at the side of the machine to a position in the machine without interference, and when the wire is in position, then the poles above the machine are removed and the couch roll returned to its normal position shown by dotted lines in Fig. 1, and the tension rolls 57 are raised so as to place the required tension on the wire.

I claim:

1. The combination of a Fourdrinier paper-making machine; a series of posts located some distance from the machine and parallel therewith; upper and lower sockets on the posts; a truck for the wire, said truck arranged to travel between the posts and the Fourdrinier machine; and a series of poles arranged to rest in the sockets on the posts and at the side of the Fourdrinier machine, so that as the truck travels between the posts and the machine, the wire is unreeled and the poles placed in position, so as to suspend the wire at one side of the machine, to be transferred onto the machine.

2. The combination of a Fourdrinier paper-making machine; a series of posts located a distance from the machine greater than the width of the wire to be applied to the machine; upper and lower sockets on the posts and supports on the machine; a series of poles mounted in the upper and lower sockets and carrying the wire to be placed on the machine; and a series of poles temporarily mounted on the machine above the carrying rolls for the wire, so that when the wire is transferred onto the machine, these temporary poles support the wire.

3. The combination of a Fourdrinier paper-making machine; a series of sockets in the floor of the mill distant from the side of the machine; a series of removable posts mounted in the sockets; brackets on the posts, each bracket having a socket; pole supports at the side of the machine; and poles extending from the sockets on the posts to the supports at the machine, so that when the wire to be placed on the machine is hung from the poles, it can be drawn onto the machine.

4. A truck for carrying and applying a making wire of a paper-making machine of the Fourdrinier type; a base for the truck; standards on the truck; brackets on the truck for supporting a roll of endless making wire;

and arms for supporting a certain number of poles in a loop of the wire, so that when the truck is traversed past the paper-making machine, the poles within the wire will be in position to support the upper run of the wire.

5. A truck for carrying and applying a making wire of a paper-making machine of the Fourdrinier type; a base having standards; brackets on the standards for supporting a roll of endless making wire; and arms for supporting a certain number of poles in a loop of the wire, so that when the truck is traversed past the paper-making machine, the poles within the wire will be in position to support the upper run of the wire, the truck having a platform for supporting a series of poles which support the return run of the wire when the wire is unwound.

6. The combination of a Fourdrinier machine; poles arranged parallel with the machine and some distance therefrom; sockets on the poles and supports at the machine; and a truck having standards, each standard having a bracket arranged to carry an endless making wire and having arms supporting a certain number of poles within a loop of the wire, said standards being spaced apart at a distance greater than the width of the wire, said truck arranged to travel in the space between the Fourdrinier machine and the posts, so that the poles can be progressively placed in the sockets of the posts and the support at the machine as the roll of wire is unwound.

35. 7. A truck for carrying and applying an endless making wire for a Fourdrinier machine, said truck being mounted on casters and having two standards spaced a distance apart greater than the width of the making wire; a bracket at the upper end of each standard; rollers on the brackets and arms also on the brackets for carrying a certain number of poles within a loop of the wire; and a spool for the wire, consisting of two poles having two heads at the ends of the poles, said heads being supported by the rollers of the bracket so as to allow the spool to turn freely on the rollers as the wire is unwound.

50. 8. A truck for carrying and applying an endless making wire for a Fourdrinier machine, said truck being mounted on casters and having two standards spaced a distance apart greater than the width of the making wire; a bracket at the upper end of each standard; rollers on the brackets and arms also on the brackets for carrying a certain number of poles within a loop of the wire; and a spool for the wire, consisting of two poles having heads at the ends of the poles, said heads being supported by the rollers of the bracket so as to allow the spool to turn freely on the rollers as the wire is unwound, 65 the truck having a platform for a certain

number of poles which are used for supporting the return run of the wire.

9. The combination in means for applying an endless wire to a Fourdrinier machine; a series of supports for the wire to be applied, said supports being located at one side of the machine; means for mounting the wire on the supports; a series of ropes arranged to be clamped to the upper and return run of the making wire; and means for simultaneously pulling upon the ropes to draw the wire from the supports at one side of the machine to a position on the machine.

10. The combination in means for applying making wire to a Fourdrinier paper-making machine, of a series of supports for wire to be applied, said supports being located at one side of the machine; means for mounting the wire on the supports; a shaft; drums on the shaft; wires leading from the drums to the upper and lower runs of the wire; and clamps on the end of each rope for clamping the ropes to the edge of the wire next to the machine, so that when the shaft is turned, all the ropes will move in unison to draw the wire from the supports onto the machine.

11. In means for applying an endless wire to a Fourdrinier paper-making machine, of a Fourdrinier machine; a series of posts located at the side of the machine at a distance greater than the width of the wire; a truck arranged to carry the endless making wire to be applied to the machine; poles supported by the machine and by the posts; a series of removable poles placed over the machine for supporting the wire as it is drawn into position on the machine; and means for drawing the wire onto the machine.

12. The combination of a Fourdrinier machine; sockets in the floor of a mill in which the Fourdrinier machine is located, said sockets being located some distance from the side of the machine; removable posts mounted in the sockets, said posts having upper and lower brackets, each bracket provided with a socket; a series of sockets on the machine and removable poles arranged to be mounted in the sockets on the machine, and in line with the poles for supporting the making wire to be applied to the machine; and means for drawing the wire into position on the machine.

13. The combination of a Fourdrinier machine; sockets in the floor of the mill some distance from the side of the machine; removable posts mounted in the sockets, said posts having upper and lower brackets, each bracket provided with an open socket; a series of sockets on the machine and removable poles arranged to be mounted in the sockets on the machine and detachable poles for supporting the making wire to be applied to the machine; sockets on the upper portion of the Fourdrinier machine and poles mounted in said sock- 130

ets; and means for drawing the wire from the poles at the side of the machine onto the poles above the machine.

14. The combination in means for applying a making wire to a Fourdrinier paper-making machine, of two sets of poles, one located on the machine and the other located at one side of the machine, so that the wire can be drawn from the poles at one side of the machine to those on the machine.

15. The combination in means for applying a making wire to a Fourdrinier paper-making machine, of two sets of poles, one located on the machine and the other located at one side of the machine; and means supporting the outer ends of the outer poles, the two poles being coupled together and in alignment so that the wire can be drawn onto the poles on the machine from the poles at one

20 side of the machine.

16. The combination in means for applying making wire to a Fourdrinier paper-making machine, of upper and lower sets of poles; means for supporting the poles at one side 25 of the machine; a series of poles located above the machine in line with the upper surfaces of the poles at the side of the machine; supporting beams for the said machine, having an extended throat for the making wire, the 30 lower set of poles at the side of the machine being in line with the upper surfaces of the lower sections of the supporting beams; and means for drawing the wire from the poles at the side of the machine onto the poles and the 35 supports of the machine.

17. The combination in means for applying making wire to a Fourdrinier paper-making machine, of upper and lower sets of poles; means for supporting the poles at one 40 side of the machine; a series of poles located above the machine in line with the upper surfaces of the poles at the side of the machine; supporting beams for the said machine, having an extended throat for the making wire; 45 and a series of tension rolls between the beams, the upper poles at one side of the machine being in line with those above the machine, and the lower set of poles being in line with the lower surfaces of the throats 50 of the beams and with the upper surfaces of the tension rolls.

18. The combination in a Fourdrinier paper-making machine, of a series of supporting beams, each beam having upper and 55 lower members spaced apart and forming an extended throat for the lower run of the making wire; anti-friction plates mounted on the upper surfaces of the lower members of the beams, which prevent the looping of the 60 wire on the beams when the wire is being placed in the machine.

19. The combination in a Fourdrinier paper-making machine, of means for supporting a making wire at the side of the machine 65 before being transferred to the machine, said

means consisting of a series of posts having upper and lower sockets; and detachable poles mounted in the sockets and arranged to support the making wire.

20. The combination in a Fourdrinier machine, of sockets on the machine; detachable 70 poles mounted in the sockets above the machine for temporarily supporting the making wire as it is being applied to the machine; a series of poles at one side of the machine; and means for supporting the outer ends of 75 said poles, the inner end of the said poles being coupled to the poles mounted above the machine, one of said poles having a pin extending into the other pole, so that the poles will be in alignment to allow the transfer of 80 the wire from the poles at the side of the machine to the poles above the machine, without interference.
